Horn Page & Cooper.

UNITED STATES PATENT OFFICE.

ALEXANDER KNOX, OF BRISBANE, QUEENSLAND, AUSTRALIA, ASSIGNOR
TO AUSTRAL WINDOW BALANCE COMPANY, A CORPORATION OF MAINE.

BALANCED WINDOW.

No. 821,510.

Specification of Letters Patent.

Patented May 22, 1906.

Application filed August 2, 1905. Serial No. 272,309.

To all whom it may concern:

Be it known that I, ALEXANDER KNOX, a subject of the King of Great Britain, and a resident of Brisbane, Queensland, Commonwealth of Australia, temporarily residing at New York, in the county and State of New York, have invented certain new and useful Improvements in Balanced Windows, of which the following is a specification, reference being had to the drawings accompanying and forming part of the same.

My invention relates to so-called "balanced" windows of the type described in United States Letters Patent to E. G. Abell, No. 788,182, granted April 25, 1905, in which the upper and lower sashes are pivotally connected with the frame in such manner as to permit substantially vertical movement of the sashes and permitting a limited swinging or turning movement of each on its pivotal connection.

The chief object of my present invention is to provide such a construction in a window of that type as will permit not only the same vertical and limited swinging movement of the sashes, but also permit either or both to be swung out of the frame, causing them to assume a position transverse thereto and even allowing them to be entirely inverted. Such movement or movements of the sashes causes them to present their outer sides to the apartment, thereby rendering all parts of the same readily accessible for cleaning without it being necessary for the attendant to stand upon the outer sill—a hazardous undertaking at best—or even to reach out of the window in such a way as to incur danger. Although capable of these various movements the window may nevertheless be locked in its closed or partly-opened positions to render the same secure against intruders.

The invention, which consists of the novel features of construction, arrangements of parts, and combinations of elements herein-after described, and more particularly set forth in the claims, will be more clearly understood when described in connection with the accompanying drawings, wherein—

Figure 1 is a front elevation of the preferred embodiment of my invention, showing both sashes in closed position. Fig. 2 is a central vertical section of Fig. 1. Figs. 3, 4, and 5 are similar sections, but showing the sashes in different positions. Fig. 6 shows a

construction of thumb-screw for securing the 55 detachable stops in position. Fig. 7 is a detailed view showing a double-shot bolt which may be used in connection with the lower sash. Fig. 8 is a perspective view showing the lower sash swung entirely out of engagement with the frame.

The upper and lower sashes of the window are indicated by 1 and 2, respectively, and 3 indicates the frame therefor. 4 and 5 are balancing-levers, one or both of which may 65 be used, pivoted, preferably, at their middle points to the inner side of the frame 3. The upper ends of the levers or holders are pivoted to plates 6 7, carried by the upper sash, and the lower ends of the same are pivoted 70 to similar plates 8 9 on the lower sash.

On the inside of the frame adjacent to the upper sash are vertical grooves, one of which is shown at 10, Figs. 2 to 5, inclusive, while similar grooves, as 11, are provided adjacent 75 to the lower sash. Extending laterally from the top rail of the upper sash and from the bottom rail of the lower sash are studs or pins 12 13, engaging the upper and lower vertical grooves, respectively. It will now be 80 clear that if the lower sash be lifted and at the same time the upper part thereof pushed out the pins or studs extending from the two will slide in their grooves and the sashes will also turn on their pivots, causing the holders 85 or levers 4 5 to assume positions out of the vertical. The window is thereby opened at top and bottom and also at the center by the lateral separation of the two sashes.

In order to give the sashes a wider range 90 of movement, as hereinbefore mentioned, the following devices are provided: 12^a and 13^a are stops or fillets removably secured in grooves 14 15 parallel with the before-mentioned grooves 10 and 11, while extending 95 transversely across the frame from the grooves 10 and 11 are releasing channels or grooves 16 17. It will now be clear that if the stops 12^a and 13^a be removed the studs which extend laterally from the sashes may 100 be caused to leave their vertical grooves and pass into the transverse slots 16 17, respectively, thereby permitting the sashes to swing freely on their pivots and to assume various positions more or less transverse to 105 the frame, as shown in Figs. 3 and 4. Continuing the movement of the sashes in the direction of the arrows in Fig. 4 and also turn-

ing the levers 4 5 on their pivots the sashes may be entirely inverted, the lower sash then being at the top of the frame and the upper sash at the bottom, as clearly shown in Fig.

5. In this way the outer sides of the sashes—that is to say, the surfaces which are normally outside of the apartment or room—are now presented inside, and are therefore readily accessible for cleaning or any other purpose.

Any suitable means may be provided for detachably securing the stops 12^a and 13^a in position in their grooves 14 15 to close the transverse channels—as, for example, the thumb-screw construction shown in Fig. 6.

In this device the plate 18 is secured to the exterior face of the stop, the screw 19 passing through the latter and penetrating the contiguous side of the frame. Each stop is provided with upper and lower devices of this character, as indicated at 20 and 21, respectively, in Fig. 1. The screw 19 is provided with a collar 22 to prevent withdrawal of the screw from the stop, the result being that when the screws are turned in the proper direction the stop will be carried out of its groove and when turned in the opposite direction the stop will be carried into and secured in its groove or seat, as will be readily understood.

If desired, the lower sash may be provided with a double-shot bolt, as in Figs. 7. and 8, composed of oppositely-extending rods or bolts 23 24, connected with an actuating device 25 of suitable character. The bolts are connected with the latter by means of right and left screw-threads, so that when the handle 26 is depressed the bolts will be withdrawn from engagement with the frame and the sash thereby unlocked, as will be readily understood. Instead of such a double bolt single bolts may be provided, one on each side of the sash, as shown at 27 and 28, Fig. 1. In either case the bolts may, if desired, be made to serve the purpose of the studs 13, as well as their function of locking the window.

From the foregoing it will be seen that my improvement enables the window to be manipulated or adjusted in such manner as to present the ordinarily inaccessible parts of the sashes to the interior of the room or apart-

ment in such manner as to eliminate all danger in cleaning the same and to make the operation much easier.

What I claim is—

1. In a window of the kind described, the combination with upper and lower sashes, of a frame therefor, a balancing-lever, pivoted to the frame and having its ends pivotally connected to the upper and lower sashes respectively, the frame being constructed to permit the sashes to be swung on their pivotal connections independently of each other, and devices removably secured to the frame to hold the sashes against such movement, as set forth.

2. In a window of the kind described, the combination with upper and lower sashes, of a frame therefor, and a balancing-lever pivoted to the frame and pivotally connected at its ends to the upper and lower sashes respectively, the frame being constructed to permit substantially vertical movement of the sashes and to permit the sashes to swing out of the frame independently of each other, as set forth.

3. In a window of the kind described, the combination with upper and lower sashes, of a frame therefor, and a one-piece balancing-lever pivoted to the frame and pivoted at its ends to the upper and lower sashes respectively, the frame being constructed to permit the sashes to be swung on their pivots and assume positions transverse to the frame, as set forth.

4. In a window of the kind described, the combination with upper and lower sashes, of a frame therefor having vertical grooves and transverse grooves crossing the latter, a balancing-lever pivoted at the side of the frame and pivotally connected at its ends with the upper and lower sashes, and studs projecting from the sides of the sashes into the vertical grooves and adapted to pass into the transverse grooves, whereby the sashes may be swung on their pivotal connections independently of each other and assume positions transverse to the frame, as set forth.

ALEXANDER KNOX.
